PADDLE BOARD FOR SKIN DIVERS OR THE LIKE

William J. Flannigan, Oxnard, Calif. (1054 Knollwood Dr., Rte. 1, Omena Lake, Sturgis, Mich. 49091)

Filed Mar. 11, 1968, Ser. No. 10,922

Term of patent 14 years

Int. Cl. D12—06

U.S. Cl. D71—1

FIG. 1

FIG. 2

FIG. 3

FIG. 4

FIG. 5

FIG. 6

FIGURE 1 is a perspective view of a paddle board for skin divers or the like showing my new design;

FIGURE 2 is a side elevational view thereof;

FIGURE 3 is a top plan view thereof;

FIGURE 4 is a bottom plan view thereof;

FIGURE 5 is a front elevational view thereof; and,

FIGURE 6 is a rear elevational view thereof.

I claim:

The ornamental design for a paddle board for skin divers or the like, substantially as shown.
